UNITED STATES PATENT OFFICE.

HENRY J. MASE, OF HUNTLEY, ILLINOIS.

DESIGN FOR A NOSE-PROTECTOR.

SPECIFICATION forming part of Design No. 32,208, dated February 6, 1900.

Application filed January 12, 1900. Serial No. 1,246. Term of patent 31 years.

To all whom it may concern:

Be it known that I, HENRY J. MASE, a citizen of the United States, residing at Huntley, in the county of McHenry and State of Illinois, have invented and produced a new and original Design for Nose-Protectors, of which the following is a specification, reference being had to the accompanying drawings, forming part thereof.

Figure 1 is a perspective view of a nose-protector, showing my new design; and Fig. 2 is a sectional view, taken on line 2 2 of Fig. 1, looking in the direction indicated by the arrows.

As shown in the drawings, the leading or material feature of my design consists of a piece A, bent to form sides a, slightly inclined from each other, as shown in Fig. 2, of the drawings. The edges a' of the sides are

outwardly curved, while the upper portion of said edges are downwardly curved, from the upper central portion of the piece A, as is shown in Fig. 1 of the drawings. The sides a are also formed with inward depressions b, somewhat below their central portions. 25

Having described my invention, what I claim as new, and desire to secure by Letters Patent, is—

The design for a nose-protector, substantially as herein shown and described. 30

In testimony whereof I have signed my name to this specification in the presence of two subscribing witnesses.

HENRY J. MASE.
